UNITED STATES PATENT OFFICE.

THEODORE WEINHART, OF BOONE, IOWA, ASSIGNOR TO THE WEINHART HEATING COMPANY, OF SAME PLACE.

STOVEPIPE ATTACHMENT AND WATER-HEATER.

SPECIFICATION forming part of Letters Patent No. 625,911, dated May 30, 1899.

Application filed April 5, 1898. Serial No. 676,545. (No model.)

To all whom it may concern:

Be it known that I, THEODORE WEINHART, a citizen of the United States, residing at Boone, in the county of Boone and State of Iowa, have invented a new and useful Stovepipe Attachment and Water-Heater, of which the following is a specification.

My objects are to utilize the waste heat (that escapes through a stovepipe) for heating water and warming the temperature of a room and building; to convey water relative to a water-heater in a stovepipe, a hot-water reservoir, a cold-water tank, and a sink; to facilitate the heating of a small quantity of water, and to regulate the temperature of water for various domestic purposes, and to clean the water-heater and stovepipe without removing it from the stovepipe.

My invention consists in a water-heater and cleaning mechanism arranged and combined with a stovepipe, a steam-tight boiler, an open tank, a sink, and a pump, as hereinafter set forth, pointed out in my claims, and illustrated in the accompanying drawings, in which—

Figure 1 is a longitudinal sectional view of the water-heater and cleaning mechanism. Fig. 2 shows the complete apparatus, partly in section.

Referring to the accompanying drawings, the reference-letter A is used to indicate a sink fixed in the top of a stationary case or frame A². At one end of this frame is a fixed tank B, adapted to be filled with cold water by pouring it in through its open top. On top of this end of the sink-frame is a raised platform B² and on this platform a boiler C. This boiler has a cock C², located above the sink, so that hot water may run therefrom into the sink. A screw-cap C³, fitted to the top of the boiler, may be removed for filling.

D is the outer cylindrical wall of the water-heater, made of sheet metal and contracted at its ends to be connected with a stovepipe of smaller diameter, as required, to inclose a double-walled cylinder D², adapted to be retained therein, to heat water therein, and to fit mechanism thereto for scraping and cleaning the outer and inner walls thereof without detaching any part thereof or disconnecting

the attachment from a stovepipe when fixed to a stove and chimney, as required for practical use.

D³ is a metal ring fitted inside of the double-walled water-heating cylinder D² in such a manner that it can be moved up and down to scrape soot from the outside surface of the inner wall.

D⁴ is a metal ring fitted in the annular space between the outside cylinder D and the double-walled cylinder D², so that it can be moved up and down to scrape the inner surface of the one and the outer surface of the other. Flexible metal rods f are fixed to the rings D³ and D⁴ to connect them in such a manner that they can be moved up and down jointly by means of rods f', connected with the outer ring D⁴ and extended upward through perforations in the cylinder D where its top portion is contracted.

g is a ring around the contracted top portion of the cylinder A and fixed to the top ends of the rods f and f' and provided with handles g' in such a manner that the ring can be lifted up and down to reciprocate the metal rings D³ and D⁴ as required to scrape and clean the outer surfaces of the double-walled cylinder and water-heater and the inner surface of the outside cylinder that is adapted to inclose the water-heater and cleaning mechanism and also to serve as a stovepipe-section.

K is a support for a lever, fixed to the under side of the platform B². K² is a lever fulcrumed to said support. K³ is a rod connecting the lever with piston in the pump-cylinder J.

In practical use water is placed in the open tank B. To heat only a small quantity quickly, the pump-handle K² is operated to force the required amount into the heater D² in the stovepipe. The valve in the pump-cylinder holds the water up, and waste heat that envelops the heater in the stovepipe is stored in the water, and a circulation through the heater D² and boiler C is established. When it is desired to heat a large quantity of water, the boiler may be nearly full and the waste heat from the stovepipe thus stored in the boiler to be utilized for warming the sur-

rounding temperature by radiation from the boiler or the hot water withdrawn from the boiler into the sink or portable receptacles for washing and other purposes in such quantity and at such intervals of time as desired.

To clean the outside surface of the water-heater D^2 and the inside surface of the stove-pipe-section D , that incloses the water-heater, I simply seize the handles g' of the ring g , 10 and thereby move the metal rings D^3 and D^4 up and down repeatedly to scrape off the soot gathered on the surfaces which they engage.

Having thus described my invention, what I claim as new therein, and desire to secure 15 by Letters Patent of the United States therefore, is—

1. A water-heater, stovepipe section and cleaner, comprising a sheet-metal cylinder contracted at its end portions to join stove- 20 pipe-sections of smaller diameter and to produce annular shoulders, a double-walled water-heater composed of two concentric cylinders united at their ends, and having inflow and outflow pipes, a metal ring fitted in the

open-ended water-heater, a metal ring fitted 25 around the outside of the water-heater, rods bent double and their ends fixed to the rings, rods fixed to the outer and larger ring and extended through perforations in the annular shoulder of the outside cylinder or stovepipe- 30 sections so the rings can be jointly operated thereby, as and for the purposes stated.

2. In a water-heating and water-conveying apparatus, the cylinder D having a contracted top end and annular shoulder, the double-walled water-heater D^2 having inflow and outflow pipes, the metal rings D^3 and D^4 , the doubled rods f fixed to the rings, the rods f' fixed to the largest ring and extended through 35 openings in the annular shoulder at the top 40 of the cylinder, and a ring g having handles g' , in combination with a stovepipe and a water-reservoir as and for the purposes stated.

THEODORE WEINHART.
